UNITED STATES PATENT OFFICE.

ANDERS CONRAD HANSON, OF STANTON, IOWA.

MITER-KNIFE.

1,228,431.

Specification of Letters Patent.

Patented June 5, 1917.

Application filed February 2, 1917. Serial No. 146,201.

To all whom it may concern:

Be it known that I, ANDERS CONRAD HANSON, a citizen of Sweden, residing at Stanton, in the county of Montgomery and State 5 of Iowa, have invented certain new and useful Improvements in Miter-Knives, of which the following is a specification.

This invention relates to certain new and useful improvements in miter knives.

10 The primary object of the invention is the provision of a cutting device after the nature of tongs or pliers whereby the cover strips of molding for screens are readily severed at the desired angle required for fitting the screen frame.

15 A further object of the device is the provision of a cutter having jaws operable in parallel planes during the employment of the device upon the work, a single closing of 20 the jaws being designed for severing a molding strip forming a desirable miter edge.

25 A still further object of the structure is the provision of a miter cutter having means for holding the work at different predetermined positions for accurately cutting the same forming uniform ends thereon, a readily removable and adjustable blade being advantageously combined with the structure.

30 In the drawing forming a part of this application and in which like designating characters refer to corresponding parts throughout the several views:—

35 Figure 1 is a side elevation of the device in its normal open position partially broken away.

Fig. 2 is a top plan view thereof.

Fig. 3 is a perspective view of the cutting block or jaw member detached, and,

40 Fig. 4 is a transverse sectional view taken upon line 4—4 of Fig. 1.

45 Referring more in detail to the drawing, it will be noted that the device broadly consists of two levers 10 and 11 connected together by a tongs-joint having a pivoting bolt 12, a cutting blade 14 being adjustably and removably attached to one end of the lever 10 by means of a mounting plate 15 and a cutting block 16 carried by the lever 11 at a point opposite the said blade and in a 50 plane perpendicular with respect thereto.

55 Each of the levers 10 and 11 is bifurcated at both sides of its pivotal connection 12, the aforementioned plate 15 being arranged within the bifurcations of both of said levers, the same being pivotally connected by a bolt 17 with the forward end of the lever 10

and having an open slot 18 at its rear end slidably mounted upon a cross pin 19 of the lever 11 rearwardly of the pivot bolt 12. The blade 14 is arranged within a slot 20 of 60 the plate 15, which plate, however, may be formed of two separate flat coöperating members with the blade 14 positioned therebetween and maintained in its adjusted position by screws 21 adapted for adjusting the 65 sections of the plate 15 upon the said blade. The blade 14 is substantially L-shaped having a cut-away portion 22 for the accommodation of the screws 21 while the same is also provided with a grooved and toothed 70 surface 23 for preventing the blade from slipping when in its operative arrangement and engaged by a rib 13 carried by the adjacent side portion of the plate 15.

75 The cutting block 16 is somewhat the shape of an arrow head having a rectangular shank 24 pivoted to the forward end of the handle 11 by means of a bolt 25 while a slot 26 is arranged in the rear end of the shank slidably mounted upon a transverse 80 bolt 27 within the bifurcated portion of the lever 10 rearwardly of the pivot bolt 12. A transverse groove 28 is provided in the shank 24 and a similar groove 29 in the inner edge of the plate 15, the said grooves being adapted for accommodating and fitting over the pivot bolt 12 when the blade and cutting block are brought together during the operation of the device and at which times the inner face 30 of the shank 24 is 85 positioned substantially in contact with the inner edge 31 of the plate 15.

90 The members hereinbefore described are preferably formed of metal while a hard-wood strip 32 is slidably positioned in dove-tailed arrangement centrally of the receiving face of the cutting block 16, a dove-tailed slot 33 being provided for the reception of the said strip 32. It will be understood that the strip 32 may be formed of 95 other material than wood if desired, such as Babbitt metal, the same being in a position to be engaged by the cutting edge 34 of the blade 14 in the cutting operation. The block 16 is adapted for the reception of the work 100 such as moldings arranged flatly thereon to be cut and extending at the desired angle transversely of the strip 32, spaced forward and rearward pairs of guides lugs 35 and 36 respectively, being provided upon the said 110 block while the rear edge of the block is rearwardly divergent and provided with up-

standing flanges 37 terminating at their inner ends adjacent the opposite edges of the strip 32.

A spring 38 is arranged between the levers 10 and 11 and coiled around a mounting pin 39 within the bifurcated portion of the lever 11 adapted for normally maintaining the blade 14 out of contact with the cutting block 16.

10 The rear end portions of the levers 10 and 11 form operating handles 40 and 41 respectively, to be grasped and operated after the manner of a pair of pliers for performing the cutting operation, a short length 15 spring 42 being hinged to the free end of the handle 40 and provided with a hook 43 for engaging over an extension 44 at the free end of the handle 41 for maintaining the blade edge 34 in contact with the cutting 20 block strip 32 when the device is not desired for use.

In operation, a screen molding such as indicated by dotted lines at 45 in Fig. 2 may be inserted between one of the lugs 36 and the adjacent flange 37 obliquely across the strip 32 when desired to cut the molding in "miter" and at an angle, it being understood that when a straight transverse cutting of the molding is desired, the latter is positioned between the lugs 35 and 36 in perpendicular arrangement with respect to the strip 32 as well as the cutting edge 34 and by forcing the handles 40 and 41 together, the molding will be severed as the occasion 35 may require.

The blade 14 may be secured within the plate 15 at different adjustments by means of the screws 21 adapting the same for cutting molds of different thicknesses. The device is serviceable in easily and quickly cutting moldings in miter for employment in securing screen cloth to screen frames. The handles 40 and 41 are preferably pressed out of iron plate with the bifurcated portions 45 thereof formed integral therewith, it being understood that by removing the bolts 17 and 25, the plate 15 and the block 16 may be removed from the levers 11 and 10 respectively, while the form of mounting therefor

herein set forth arranges the cutting edge 50 34 at all times parallel with respect to the block 16 and the contact strip 32.

What I claim as new is:—

1. A miter knife comprising pivoted levers, a cutting block pivoted to one of said levers having rearwardly diverging portions of V-shape extending to opposite sides of the levers and formed with upright flanges upon the working face of the said block, work-engaging guide lugs carried by the said block spaced from the said flanges, one face each of two of said lugs being parallel to the adjacent upright flange, the other two faces of said two lugs, and two faces of the remaining lugs being parallel, and a cutting blade carried by the other lever, whereby the desired direction-angle and straight edge may be cut. 55

10 2. A miter knife comprising pivoted levers, a cutting block pivoted to one of said levers having rearwardly diverging portions formed with upright flanges upon the working face of the said block, work-engaging guide lugs carried by the said block spaced from the said flanges, a knife-engaging strip 75 arranged centrally of the cutting block between the said lugs and flanges, a plate pivoted to the adjacent end of the other lever, movement limiting pins carried by said levers for the said block and plate, and a cutting blade adjustably carried by the plate 80 having a cutting edge arranged parallel to the said strip. 85

3. A cutting knife comprising pivoted levers, a substantially arrow-head shaped work-engaging cutting block having a shank pivoted to the forward end of one of said levers and arranged with a slot in its rear end, a guide pin carried by the other one of said levers arranged within said slot, work-positioning lugs and flanges upon the said plate, 90 a cutting strip of relatively softer material having dove-tailed engagement centrally of said block and a cutting knife arranged adjacent said block. 95

In testimony whereof I affix my signature.

ANDERS CONRAD HANSON.

Copies of this patent may be obtained for five cents each, by addressing the "Commissioner of Patents, Washington, D. C."
